UNITED STATES PATENT OFFICE.

FRED F. RICKER, OF PHILADELPHIA, PA., ASSIGNOR TO BROMLEY BROTHERS, (LIMITED,) OF SAME PLACE.

DESIGN FOR A CARPET.

SPECIFICATION forming part of Design No. 14,775, dated February 19, 1884.

Application filed January 2, 1884. Term of patent 3½ years.

To all whom it may concern:

Be it known that I, FRED F. RICKER, a citizen of the United States, and a resident of Philadelphia, Pennsylvania, have invented or 5 produced a new and original Design for a Carpet-Pattern, of which the following is a specification.

My design is fully shown in the accompanying drawing, and comprises the two figures 10 A and B, arranged upon a background ornamented with small square figures, each composed of spots. Each of the figures A and B comprises leaves, blossoms, and stems, as fully shown in the drawing. The figure A is shown 15 entire; but the figure B is shown in four parts, which, it will be understood, are united in the complete pattern.

I claim—

The design for a carpet-pattern, said design comprising the figures A and B, each composed of leaves, blossoms, and stems, all substantially as described and shown. 20

In testimony whereof I have signed my name to this specification in the presence of two subscribing witnesses.

FRED F. RICKER.
